US00D827589S

(12) **United States Design Patent** (10) Patent No.: **US D827,589 S**
(45) Date of Patent: ** Sep. 4, 2018

(54) **HEAT SINK**

(71) Applicant: **SUMITOMO SEIKA CHEMICALS CO., LTD.**, Hyogo (JP)

(72) Inventors: **Seiji Bando**, Hyogo (JP); **Hirotake Moriyama**, Hyogo (JP)

(73) Assignee: **SUMITOMO SEIKA CHEMICALS CO., LTD.**, Hyogo (JP)

(**) Term: **15 Years**

(21) Appl. No.: **35/502,712**

(22) Filed: **Sep. 30, 2016**

(80) **Hague Agreement Data**

Int. Filing Date: **Sep. 30, 2016**

Int. Reg. No.: **DM/093472**

Int. Reg. Date: **Sep. 30, 2016**

Int. Reg. Pub. Date: **Mar. 31, 2017**

(57) **CLAIM**

The ornamental design for a heat sink, as shown and described.

DESCRIPTION

1., 3.-4. Heat sink

1.1 : Front

1.2 : Back

1.3 : Top

1.4 : Bottom

1.5 : Left

1.6 : Right

1.7 : Top perspective view

1.8 : Bottom perspective view

1.9 : Cross-sectional

3.1 : Front

3.2 : Back

3.3 : Top

3.4 : Bottom

3.5 : Left

3.6 : Right

3.7 : Top perspective view

3.8 : Bottom perspective view

3.9 : Cross-sectional

4.1 : Front

4.2 : Back

4.3 : Top

4.4 : Bottom

4.5 : Left

(Continued)

4.6 : Right**4.7** : Top perspective view**4.8** : Bottom perspective view**4.9** : Cross-sectional

The articles are heat sink for heat release and cooling of electric and electronic equipment, such as television integrated circuits and lighting apparatus; reproduction No. **1.9** is a cross-sectional view sectioned vertically at the center of the right view No. **1.6**; reproduction No. **3.9** is a cross-sectional view sectioned vertically at the center of the right view No. **3.6**; reproduction No. **4.9** is a cross-sectional view sectioned vertically at the center of the right view No. **4.6**.
